UNITED STATES PATENT OFFICE

2,518,333

FROZEN CONFECTION VENDING MACHINE
UNIT

James E. Kendig, Oreland, Pa., assignor to Eastern Engineering & Sales, Inc., Philadelphia, Pa., a corporation of Pennsylvania

Application January 14, 1949, Serial No. 70,956

16 Claims. (Cl. 312—97.1)

1

This invention appertains to novel and useful improvements in equipment for dispensing articles.

An object of this invention is to dispense articles, particularly frozen confections by means of cam actuated ejectors rendered operative upon movement of a rotary magazine, the ejectors having a rotative movement with the magazine, while the cams are retained relatively stationary. The ejectors operate on the frozen confections in order to break the adhesion or the adhesion bond between the frozen confections and the rotary magazine thereby imparting an initial thrust to the article which is about to be dispensed, the completion of the dispensing operation taking place by means of the force or pull of gravity.

Another object of this invention is to removably and replaceably mount a composite unit in a specially provided cabinet or an existing cabinet having refrigeration facilities therein, whereby the unit may be removed for repair purposes or, whereby the unit may be conveniently and easily slipped into place within substantially all types of conventional vending machine cabinets.

A further object of this invention is to incorporate means in the unit rendering filling and re-filling rapid, easy and facile, and incorporate in the structure of the unit such mechanism as to render it possible to load the rotary magazine from the top thereof simply rotating the magazine sufficiently to place frozen confections or other articles therein, the cam actuated ejector mechanism being inoperative at this time.

A still further object of this invention is to prevent the failure of ejecting a frozen confection when the plurality of wheels forming the rotary magazine are moved such an amount that one wheel exhausts its supply and the next adjacent wheel is picked up in the rotary movement.

A still further object of this invention is to utilize frozen confections which are wrapped by the manufacturer, it being unnecessary to wrap the said confections specially or in a special manner thereby materially reducing labor costs involved and the cost of additional packaging material.

And another object of this invention is to store the frozen confections such as ice cream bars or the like so that they do not contact each other, each bar being stored individually in a separate compartment thereby avoiding the possibility of disfigurement due to inadvertent fall in temperature within the conventional cabinet within reasonable limits which would ordinarily occur more

2

quickly if the frozen confections were stacked or stored in very confined quarters.

Ancillary objects and features of novelty will become apparent to those skilled in the art, in following the description of the preferred form of the invention, illustrated in the accompanying drawings, wherein:

Figure 1 is an elevational front view of a typical cabinet having the invention disposed therein for operation;

Figure 2 is an elevational view similar to that shown in Figure 1, the door of the cabinet being in the open position;

Figure 3 is a longitudinal sectional view taken substantially on the line 3—3 of Figure 1 and in the direction of the arrows, showing particularly the internal structure of the magazine and ejector unit;

Figure 4 is an elevational side view of the unit separated from a cabinet;

Figure 5 is a sectional view taken substantially on the line 5—5 of Figure 4 and in the direction of the arrows;

Figure 6 is an enlarged fragmentary portion of the structure illustrated in Figure 3 and showing particularly the cam operated ejectors and magazines both when a frozen confection is being discharged and before another frozen confection in an adjacent magazine wheel is discharged;

Figure 7 is an enlarged fragmentary perspective view of a portion of the magazine and cam actuated ejectors;

Figure 8 is a fragmentary perspective view of a portion of the rotary magazine showing the clutch mechanisms between the wheels thereof;

Figure 9 is an elevational schematic view of the magazine illustrating particularly the dummy or blank compartments in the wheels;

Figure 10 is an enlarged sectional detail of construction showing particularly the sliding closure for the discharge opening which is used to receive and guide frozen confections as they are ejected, and;

Figure 11 is an enlarged perspective view of one of the cams used in conjunction with the ejectors and showing partially the means for raising the cams to the inoperative position and lowering the cams to the operative position.

Various vending apparatus and equipment is commonly used. In each vending machine there is certain equipment used for the purpose of discharging an article such as a frozen confection, non-frozen confections, cigarettes, liquid refreshments and others. The instant invention deals with that type of apparatus which is adapted to

discharge frozen confections such as ice cream, popsicles and many others. The same structure used for discharging this type of confection may be used in conjunction with other types of articles which are to be discharged.

Generally, the cabinet used in conventional equipment is substantially the same from a structural viewpoint. Insulated walls are used, a compartment is provided for the purpose of accommodating refrigeration equipment and coin receiving appurtenances and treatment apparatus is carried by and partially within the cabinet. Hence, for the purposes of this invention a substantially conventional cabinet is utilized and illustrated which has a door 10 sealed by means of a gasket 12 when in the closed position in the door opening of the cabinet 14. The said door 10 opens a compartment 16 wherein there is disposed a portable frozen confection article dispensing unit.

In dispensing frozen confections by utilizing structure now conventional which is incidentally of various mechanical detail, a major problem has arisen. Due to the low temperature or heat value within the cabinet which is necessary to retain the frozen confection in the firm state, an adhesion bond is set up between the article to be dispensed and the magazine whether it be of the compartmented type or other types. Hence, means is provided in the portable unit disclosed herewith for an initial force to break this bond.

Support frame structure

A support or frame generally indicated at 28 includes the necessary structural elements for retention of various components of the device. Included in the support or frame is a pair of sides 22 and 24 respectively held in spaced relationship with each other by means of cross member 26, 28, 30 and 32 respectively. This forms a frame having open ends and an open top and bottom.

Fixed to the upper cross members 28 and 30 respectively is a pair of smoothly curved baffles 34 and 36 respectively which cooperate to form a guide. It is noted at this point that any suitable fastening means may be used in conjunction with the frame structure such as spot welding, screwing, riveting or others. The inner ends of the baffles 34 and 36 respectively are bent generally downward and are spaced from each other to form a discharge opening 38. The baffle 34 has its end 40 inclined at an angle with respect to the horizontal and in a down direction in order that the frozen confections may be guided in the discharge travel thereof. Stiffening members in the form of angles 42 or other forms are attached to the sides 22 and 24 and also to the ends of the two baffles 34 and 36. Openings to be identified subsequently are provided in the plates 22 and 24 respectively in order to accommodate bearings 40 for the support of various shafts.

Rotary magazines

Means for storing and maintaining frozen confections such as the packaged ice cream 45 having a handle 46 extending therefrom, is provided. The instant device is designed primarily for use in conjunction with this type of confection and hence certain small structural provisions such as openings for accommodation of the ice cream handles 46 is provided in the rotary magazine.

The magazine consists of one or more wheels. In Figure 9 four wheels are illustrated and are indicated at 48, 50, 52 and 54 respectively. In this instance each wheel is provided with a rim

(Fig. 8) 56 connected to a hub 58 by means of a number of spokes 60. A shaft 62 is disposed in all of the hubs and has its ends mounted in apertures provided in the plates 22 and 24 respectively which have suitable bearings therein.

A clutch mechanism is disposed between adjacent wheels and is of a type which is rendered operative for coupling adjacent wheels together after the first wheel has traveled somewhat less than 360°.

One of the wheels 48 is pinned to the shaft, being attached thereto for movement therewith through any suitable structure such as the pin 64 which is disposed in a suitable groove formed in the shaft 62 and in a complementary groove in the hub 58. Hence, upon rotation of the shaft 62 the wheel 48 will be correspondingly rotated.

A pin 66 is carried by the hub 58 projecting from the end thereof substantially parallel to the longitudinal axis of the shaft 62. This pin engages another pin 68 which is carried by a collar 70 mounted for free rotation on the shaft 62 between adjacent wheels 48 and 50. It is seen that the collar 70 will begin to rotate prior to a completion of a 360° of rotation of the wheel 48. The pin 68 projects laterally from the collar 70 and is disposed in an enlarged opening 74. This enlarged opening is formed in the hub 76 of the wheel 50. An identical clutch mechanism is provided between adjacent wheels to pick up for movement progressive wheels along the shaft 62.

The reason for utilizing the enlarged opening 74 is brought out by inspection of the schematic showing in Figure 9. In each wheel there is one dummy compartment or blank compartment which does not accommodate a frozen confection 45. They are identified as A, B, C, and D. The distance (linear) of a point on the periphery of each wheel caused by the presence of the two pins 66 and 68 is reflected in the disposition of the blank compartments indicated at A and B, C, D in phantom. This is the position of the dummy or blank compartments when all of the wheels in the magazine are coupled together by the clutch mechanisms so that the rotary magazine moves as a unit.

At the periphery of each wheel means is provided for the purpose of accommodating the frozen confections 45. This means consists of a pair of substantially circular side pieces 80 and 82 respectively provided in suitable recesses 84 and 86 in the rim 56 of the wheel 48. Each wheel is identical in structure. The preferred material of construction of these side pieces is a phenolic condensate or some other suitable plastic material. However, any suitable materials may be used.

Means for spacing the sides 82 and 84 and also for dividing the periphery of the wheel 48 into compartments is provided. The preferable means consists of aluminum bars 88 covered with a plastic material. Due to the thermal properties of plastic material as well as the anti-corrosive properties thereof it has been found preferable to utilize this type of material for the formation of the compartments having the frozen confection disposed therein.

Central openings 92 are provided in the rim 56 of the wheel in order to accommodate the handle 56 of each frozen confection. There is one passage or opening 92 provided for each compartment. As seen in Figure 7, the frozen confection is adapted to have the handle projecting through this passage in each instance and the

actual body of the confection is disposed between adjacent bars 88.

Means for operating the shaft 62 a predetermined distance is provided. The preferable means consists of conventional elements such as the motor 94 (Fig. 2) carried by the frame or support structure, a gear 96 driven by the motor and having a chain 98 extending therearound, and a larger gear 100 fixed to the shaft 62 also having the chain 98 entrained therearound. Other types of drives such as a belt and pulley, worm and gear and the like may be used. However, it has been found that the chain drive is the most inexpensive type of driving connection which is positive enough in action.

Coin control mechanisms of the type which reject slugs, give the correct change and perform other functions are used. By the disposition of a contact on the last wheel 54 to rotate and a complementary contact on the support for operative engagement therewith, a visual sign is given when the magazine is empty. This structure is however, purely conventional and need not be considered in detail. As is very well known, the application of a coin in one of these coin control mechanisms operates the motor 94 for a duration and only a predetermined amount. This predetermined amount is sufficient to move one of the compartments in one of the wheels a distance sufficient to allow one frozen confection 45 to pass directly over the discharge opening 38.

Cam actuated ejector mechanism

As the wheels of the rotary magazine are operated, it is seen from inspection of Figure 5 that a frozen confection is emitted from the magazine. However, when handling frozen confections it is sometimes impossible to have them ejected by means of gravity only. Hence, in the instant case there is the combination of the pull of gravity and a positive displacement means. This positive displacement means is used solely for the purpose of breaking the adhesion between the frozen confection and the rim 56 and/or the sides 88 and 82.

A shaft 104 is mounted for rotation in suitable bearings provided in the plates 22 and 24 respectively. This shaft has a non-circular end portion 106 (Fig. 11) for accommodation of the handle 108. This shaft extends entirely through the area between both plates and has pairs of links 110 and 112 respectively carried thereby. One pair of links is provided for each space between the magazine wheels. Hence, as disclosed and in this instance there are three pairs in all. Each pair of links 110 and 112 is pinned to a pitman 114 which is mounted for rotation on a shaft 116 which extends between the sides 22 and 24. Operating members 118 and 120 respectively have a shaft 122 extending therethrough which is mounted for rotation in suitable bearings provided on the plates 22 and 24. Also extending through these operating members 118 and 120 is the shaft 116. Stops 124 and 126 respectively extend across the operating members 118 and 120 and are disposed in flanking relationship with respect to a cam support arm 128. The opposite end of the cam support arm is fixed on a shaft 131 for pivotal movement. This shaft (Fig. 5) is mounted for rotation in suitable bearings provided in the plates 22 and 24 respectively.

In operation of the cam support arm 128 for a reason to be described subsequently, it is necessary only to impart rotative movement to the

shaft 104 by means of the handle 108. Since the links 110 and 112 respectively are rigid therewith at one end, the shaft 116 is laterally displaced through the intermediate structure of the pitman 114. Hence, each pair of operating links 118 and 120 respectively will pivot about the shaft 122 as an axis. Assume that the handle 108 is rotated in a clockwise direction, then, the stop 126 engages the undersurface of the arm 128 thereby raising the same. In the event that the cam support arm 128 is already in the raised position as shown in phantom in Figure 5, counterclockwise rotation of the handle 108 will bring the stop 124 into play, lowering the cam support arm 128 and of course, simultaneously lowering the stop 126 which is used as a seat for the cam support arm 128.

The baffles 34 and 36 which cooperate to form a guide for the frozen confections 45 to prevent their slipping from the rotary magazine, have slots 130 provided therein and the cam supporting arms 128 extend therethrough (Figure 4). Not only do these slots allow free passage of these arms but they serve a secondary function and that is to permit the cool air to be blown therethrough to insure refrigeration in the immediate region of the frozen confections. Other slots may be provided in the sides 22 and at various and sundry other places as the dictates of sound engineering principles suggest.

In Figure 6 there is disclosed the relationship of the cam support arms 128 and the wheels of the rotary magazine. The cams are disposed adjacent the sides 88 and 82 of each wheel for the operation of ejectors 134 and 136 which are mounted for movement through suitable passages 138 formed in the hub 56. As one wheel is rotated, a cam 139 is engaged by the outer edge of the ejector thereby urging it radially with respect to the hub of the wheel. It is seen that two ejectors are provided for each wheel and hence, two cams are utilized. One cam is disposed on one of the arms 128 and the other cam used in conjunction with the same wheel is disposed on a second adjacent arm 128.

The shape of the ejectors 134 or 136 is identical. They are L-shaped rods having the longer legs extending through the passages 138 and the shorter legs adapted for disposition on a flat side of a frozen confection 45.

Means opposing the cam operation of the ejectors 134 and 136 reacts on the shorter legs of the ejectors and the hub 56 of the pertinent wheel. Preferable means consists of a resilient element such as a spring 140 which is attached at one end to the inner surface of the wheel hub by means of a pin or the like and attached at the other end to the shorter leg of the L-shaped ejectors. Suitable passages 142 are provided in the hub of each wheel for accommodation of these springs.

With regard the means opposing the operation of the ejectors, the springs may be attached in other mannerisms but with regard the particular type of confection under discussion it is best to have them disposed very close to the hub and by the utility of the passages 142 the spring 140 may be stored substantially entirely therein, usurping no space on the outside surface of this hub.

In instances wherein interference would be occasioned by the existence of the spokes 60, cutouts or notches 148 (Fig. 8) are provided.

Method of loading

The unit is adapted to be loaded from the top.

Reference to Figure 9 shows schematically the position of the blank or dummy compartments which are in axial alignment with the shaft 62. Initially however, the crank or handle 108 is rotated in such direction as to lift the cams so that they will not contact any of the ejectors upon rotation of the magazine wheels. Due to the linkage involved in the means for raising and lowering the cam support arms, a dead center position is arrived at whereby the cam support arms will simply remain in the upright position. Then, the handle 150 is operated for the purpose of moving a sliding closure 153 so that the discharge opening 38 is closed. This sliding closure 153 has in general the same configuration as the guide.

The handle 150 is attached to a shaft 152 which is rotatively mounted in the plates 22 and 24 respectively. Links 154 and 156 respectively are attached rigidly to the shaft 152 and moved therewith. These links have pairs of pitman rods 158 secured thereto and also to suitable ears 160 which are in turn carried by the outer surface of the closure 153. Accordingly, upon rotative movement of the shaft 152 the closure 153 is slid through a suitable opening 164 formed in the end of the baffle or guide element 36. Additional guides 166 are fixed to the sides 22 and 24 in order that the said closure 153 may slide smoothly. The end of the closure may be bent downwardly as shown in Figure 10 to form a stop. Hence, with the discharge opening 38 closed by means of the closure 153 it is not possible for one or more of the frozen confections to simply fall from the rotary magazine if no adhesion bond is present.

After all of the magazine wheels are filled with frozen confection, the blank compartments A, B, C, and D are moved to the down position that is, they are disposed directly over the closure 153. The cams are then lowered by means of the handle 108 thus pressing all of the pertinent ejectors downwardly as if to eject a frozen confection. But, since the dummy compartments are in the full down position they are simply harmlessly biased or urged downwardly.

Through the medium of purely conventional switches provided in the wiring of the motor and other apparatus at pertinent places, the motor may be rendered inoperative during the loading period. Now, since the machine has been loaded, this switch may be operated thereby energizing the circuit having the motor therein thereby placing the apparatus in readiment for reception of a coin of the proper denomination.

Operation

After depositing a coin in the proper slot in the front of the apparatus, if it is the proper denomination due to the conventional mechanism disposed in conjunction with the slot, the motor 94 will be operated a small amount. The operation of the motor is reflected in movement of the rotary magazine wheel 48. As described, all of the rotary magazine wheels have their dummy or blank compartment disposed immediately above the discharge opening 38. But, since the wheel 48 is the only one which moves, the two pertinent ejectors (in that wheel) are the only ones which are operated on in conjunction with the cams 139. This urges the ejectors downwardly and in a radial direction with respect to the hub 56 of the wheel 48 against the tension of the spring elements 140. Hence, the ice cream or other type of frozen confection is broken loose

from the bond set up by the freezing of the frozen confection wrapper to the various elements. For illustrative purposes and clarity of disclosure, the frozen confections are shown without having the wrapper thereon. However, the wrappers are actually what are attached.

The ejectors urge the frozen confection from the magazine having the confection therein from both sides of the confection thereby moving it smoothly and evenly.

Once the confection has had this bond broken it is free to fall by gravity through the outlet chute 180 which is formed in the cabinet 14. Partitions 182, 184, 186 and 188 respectively are disposed in this outlet chute 180 dividing the same into minor chutes for reception of all of the frozen confections in a single magazine wheel. An outlet door 190 is mounted for movement in front of the vending machine and in communication with the end of the discharge chute 180. It is through this door 190 that an individual receives the frozen confection after it has been discharged.

After the wheel 48 is moved a rotative amount equal to 360° less the included angle of the dummy or blank compartment B, the clutch mechanism is rendered operative thereby carrying with it for rotation the second wheel 50. Hence, after the last frozen confection is discharged from the wheel 48 the dummy A has been rotated around to the discharge opening and moves directly thereover with the movement of the first full compartment in the wheel 50. This identical operation is completed until all of the four rotary magazine wheels have come in direct vertical alignment with the discharge opening 38. At that time, through the medium of conventional contacts placed on the wheel 54 and on a stationary element visual sign is given on the door 10 so that an indication for refilling is set forth and so that further money will not be placed in the apparatus. Means for preventing the acceptance of further money when the machine is completely empty is provided. This may consist of a baffle which through electrical means is inserted in the coin slot and is conventional in description.

When the vending machine is empty the closure 153 is operated to move the same to the position as disclosed in Figure 10 and the cams are lifted by rotation of the appropriate handle 108. The magazine wheels are then reloaded and all of the blank or dummy compartments are disposed as shown in Figure 9 and as described previously. The apparatus is then in condition for further operation.

In the event of the necessity of repairs it is only necessary to slide the entire unit from the cabinet and replace the same in order that the defective unit may be taken to a central location or plant for repair.

It is apparent that variations may be made without departing from the spirit of the invention. Accordingly, limitation is sought only in accordance with the scope of the following claims.

Having described the invention, what is claimed as new is:

1. A storage and dispensing unit for use with a cabinet having a compartment therein comprising a support disposed in said compartment, a rotary magazine carried by said support and a cam actuated dispenser carried by said support rendered operative in response to a partial radian 70 of travel of said magazine, means attached to

said support adjacent the lower periphery of said magazine forming a guide for articles prior to dispensing from the magazine and having a discharge opening, and a manually operable closure for said opening.

2. A storage and dispensing unit for use with a cabinet having a compartment therein comprising a support disposed in said compartment, a rotary magazine carried by said support and a cam actuated dispenser carried by said support rendered operative in response to a partial radian of travel of said magazine including a plurality of ejectors mounted for radial movement in said magazine, and means attached to said ejectors and said magazine opposing the operation of said ejectors to return said ejectors.

3. A portable dispensing unit adapted to be removably disposed in a vending machine having refrigeration facilities comprising a support, a plurality of rotary magazines carried by said support, means for coupling adjacent magazines upon substantially a single revolution of one of the adjacent magazines, cams disposed within the periphery of said rotary magazines, means movably carried by said support holding said cams whereby said cams may be moved toward and away from the periphery of each magazine, and means carried by said magazines and operable by said cams upon rotation of said magazines for urging articles from the magazines to break the adhesion bond between the articles and the magazines.

4. A portable dispensing unit adapted to be removably disposed in a vending machine having refrigeration facilities, said unit comprising a support, a plurality of rotary magazines carried by said support, means for coupling adjacent magazines upon substantially a single revolution of one of the adjacent magazines, cams disposed within the periphery of said rotary magazines, means movably carried by said support holding said cams whereby said cams may be moved toward and away from the periphery of each magazine, means carried by said magazines and operable by said cams upon rotation of said magazines for urging articles from the magazines to break the adhesion bond between the articles and the magazines, a motor secured to said support drivingly connected with said magazines, a guide attached to said support and disposed beneath the lower periphery of said magazines, a dispensed article discharge opening in said guide, a closure carried by said support for said opening, and means for operating said closure to the opening closing position to prevent articles from passing through said opening, when said magazines are being loaded during free and non-discharging rotation of said magazines.

5. In a vending machine having a refrigeration mechanism the improvement which comprises: a portable dispensing unit removably disposed in the machine and including a support frame, a shaft mounted for rotation in said frame and having a rotary magazine carried thereby, a plurality of compartments in said magazine adapted to accommodate a frozen confection, substantially radial passages in said magazine, frozen confection ejectors disposed in said passages, and means carried by said frame for operating each ejector in response to rotary movement of said magazine.

6. In a vending machine having a refrigeration mechanism the improvement which comprises: a portable dispensing unit removably disposed in the machine and including a support

frame, a shaft mounted for rotation in said frame and having a rotary magazine carried thereby, a plurality of compartments in said magazine adapted to accommodate a frozen confection, substantially radial passages in said magazine, frozen confection ejectors disposed in said passages, means carried by said frame for operating each ejector in response to rotary movement of said magazine including a plurality of cams, said magazine including a plurality of wheels with said cams disposed therebetween, and means reacting on said wheels and said ejectors opposing the cam operation of said ejectors.

7. In a vending machine having a refrigeration mechanism the improvement which comprises: a portable dispensing unit removably disposed in the machine and including a support frame, a shaft mounted for rotation in said frame and having a rotary magazine carried thereby, a plurality of compartments in said magazine adapted to accommodate a frozen confection, substantially radial passages in said magazine, frozen confection ejectors disposed in said passages, means carried by said frame for operating each ejector in response to rotary movement of said magazine including a plurality of cams, said magazine including a plurality of wheels with said cams disposed therebetween, and means reacting on said wheels and said ejectors opposing the cam operation of said ejectors, a blank compartment in each wheel, and a clutch mechanism connecting adjacent wheels together for rotation upon movement of one wheel with respect to the next adjacent wheel an angle of 360° less the included angle of the blank compartment to insure discharge during the period of operation of transition from one wheel to the next adjacent wheel.

8. For use in a cabinet having a refrigerated compartment, a dispensing unit including a rotary magazine having a plurality of open faced compartments adapted to accommodate articles of frozen confection, article ejectors carried for movement in said compartments by said magazine, and means operatively engaging said ejectors and operating one of said ejectors when said magazine is rotated a predetermined distance.

9. The combination of claim 8 and said ejector operating means including a cam, and a motor drivingly connected with said magazine for rotating said magazine.

10. For use in a cabinet having a refrigerated compartment, a dispensing unit including a rotary magazine having a plurality of open faced compartments adapted to accommodate articles of frozen confection, article ejectors carried for movement in said compartments by said magazine, means operatively engaging said ejectors and operating one of said ejectors when said magazine is rotated a predetermined distance, non-rectilinear spacers in said magazine partially forming said compartments, an article guide having a discharge opening and disposed adjacent the lower portion of said magazine whereby a dispensed article may fall by gravity from the magazine through the opening after fracturing of the adhesion bond by one of the ejectors.

11. For use in a cabinet having a refrigerated compartment, a dispensing unit including a rotary magazine having a plurality of open faced compartments adapted to accommodate articles of frozen confection, article ejectors carried for movement in said compartments by said magazine, means operatively engaging said ejectors and operating one of said ejectors when said

magazine is rotated a predetermined distance, non-rectilinear spacers in said magazine partially forming said compartments, an article guide having a discharge opening and disposed adjacent the lower portion of said magazine whereby a dispensed article may fall by gravity from the magazine through the opening after fracturing of the adhesion bond by one of the ejectors, and resilient means secured to said magazine and said ejectors opposing the cam operation of said ejectors.

12. A dispensing unit comprising a frame having a smoothly curved guide fixed thereto, a discharge opening in said guide, and a closure carried by said frame for said opening, a magazine mounted for rotation in said frame and including a plurality of wheels having peripherally open compartments therein adapted to accommodate frozen confection articles, said guide being fixed to the lower portion of said frame and forming a closure for the peripherally open compartments as they rotate past said guide, a plurality of cams, means supporting said cams between said wheels, and ejectors partially disposed in said compartments carried by said wheels operable by said cams upon rotation of said wheels to destroy the adhesion bond between the wheels and frozen confection articles.

13. A dispensing unit comprising a frame having a smoothly curved guide fixed thereto, a discharge opening in said guide, and a closure carried by said frame for said opening, a magazine mounted for rotation in said frame and including a plurality of wheels having peripherally open compartments therein adapted to accommodate frozen confection articles, said guide being fixed to the lower portion of said frame and forming a closure for the peripherally open compartments as they rotate past said guide, a plurality of cams, means supporting said cams between said wheels, and ejectors partially disposed in said compartments carried by said wheels operable by said cams upon rotation of said wheels to destroy the adhesion bond between the wheels and frozen confection articles, said cams being disposed substantially in vertical alignment with said dis-

charge opening thereby operating only the ejectors above the opening whereupon after the adhesion bond is broken, the frozen confection articles fall due to the force of gravity.

14. A dispensing unit comprising a frame having a smoothly curved guide fixed thereto, a discharge opening in said guide, and a closure carried by said frame for said opening, a magazine mounted for rotation in said frame and including a plurality of wheels having peripherally open compartments therein adapted to accommodate frozen confection articles, said guide being fixed to the lower portion of said frame and forming a closure for the peripherally open compartments as they rotate past said guide, a plurality of cams, means supporting said cams between said wheels, and ejectors partially disposed in said compartments carried by said wheels operable by said cams upon rotation of said wheels to destroy the adhesion bond between the wheels and frozen confection articles, each wheel having one dummy compartment, clutches disposed between said wheels connecting successive wheels for movement when the dummy compartment of one wheel is disposed adjacent the discharging position.

15. The combination of claim 14 and means carried by said frame for moving said cams to a position spaced from said ejectors whereby said ejectors are inoperative upon rotation of said wheels.

16. The combination of claim 15 and manually operable means for actuating said closure.

JAMES E. KENDIG.
